UNITED STATES PATENT OFFICE.

MACK C. BARRY, OF ATLANTA, GEORGIA, ASSIGNOR OF ONE-HALF TO
ANDREW L. BARRY, OF ATLANTA, GEORGIA.

CROSSING-GATE.

SPECIFICATION forming part of Letters Patent No. 703,754, dated July 1, 1902.

Application filed March 10, 1902. Serial No. 97,469. (No model.)

To all whom it may concern:

Be it known that I, MACK C. BARRY, a citizen of the United States, and a resident of Atlanta, in the county of Fulton and State of Georgia, have invented a new and Improved Crossing-Gate, of which the following is a full, clear, and exact description.

This invention relates to improvements in gates for railway-crossings; and the object is to provide a gate with novel and simple releasing and resetting devices arranged along the track and adapted to be operated by a locomotive passing along the track.

I will describe a crossing-gate embodying my invention and then point out the novel features in the appended claims.

Reference is to be had to the accompanying drawings, forming a part of this specification, in which similar characters of reference indicate corresponding parts in all the figures.

Figure 1 is a perspective view showing a gate embodying my invention. Fig. 2 is a detail showing one of the release-operating levers employed. Fig. 3 is a plan showing a resetting-lever employed. Fig. 4 is a sectional view showing the locking mechanism, and Fig. 5 is a perspective view of a portion of the gate-bar.

The gate comprises a frame arranged at one side of a track, as here shown, and consisting of uprights or posts 1 2, connected at the top by a cross-timber 3. The post 2 may be made in the form of two strips, and arranged between these strips is the gate-bar 4, the pivotal connection of said gate-bar being near the lower end of the post 2. Rearward of its pivotal point the gate is weighted, as at 5, so that when released it will be automatically swung upward to the position indicated in full lines in Fig. 1. From the gate, rearward of its pivot, a rod or wire 6 extends to a connection with one member of an angle-lever 7, pivoted in standards on the cross-timber 3, and from the other or vertically-disposed member of this angle-lever a link 8 extends to a connection with the upper end of a lever 9, mounted in standards 10 on said cross-timber, and from the opposite side of the upper end of this lever 9 a spring 11 extends to a fixed post or standard 12 on the

cross-timber. This spring 11 is designed to swing the gate to its closing position, as will be hereinafter described.

The lower end of the lever 9 is connected by means of a link or rod 13 with the upwardly-disposed member of an angle-lever 14, mounted in a standard on the cross-timber 3, and from the other member of this angle-lever 14 a draw-rod 15 extends downward to connection with the horizontally-disposed member of an angle-lever 16, pivoted in a standard 17, arranged at the base of the post 1.

Arranged at one side of the track or between the track and the gate and in line with the angle-lever 16 is a guide-frame 18 for a locking-block 19. This locking-block 19 has a stem 20, extended loosely through the top member of the frame 18, and arranged between this said top member and the block is a spring 21, which tends to force the block 19 downward to its locking position with a sliding bar 22, mounted to slide transversely through the frame 18 and having bearings in standards 23. This bar 22 is provided with a notch, as clearly shown in Fig. 4, to receive the end of the block 19. A spring 24 connects one end of the sliding bar 22 with the downwardly-disposed member of the angle-lever 16. This spring will relieve the parts from undue shock when operated by a train.

Pivoted to one side of the frame 18 is an angle-lever 25, which at its upper end has pivotal connection with the block 19, and from its lower end a draw-rod 26 extends to a connection with a rock-shaft 27, arranged at one side of the track, and connected to the inner end of this rock-shaft 27 is a lever 28, designed to be engaged by a part carried by a train—such, for instance, as a wheel or tapet-arm attached to a locomotive. At the opposite side of the frame 18 is a pivoted lever 29, the upper end of which is connected to the block 19, while from the lower end a draw-rod 30 extends to connection with one member of a horizontally-swinging angle-lever 31, and from the other member of this angle-lever a rod 32 extends across the track and inner rails to connection with one member of a horizontally-swinging angle-lever 33, the other arm of the angle-lever 33 having a draw-

100

rod connection 34 with a rock-shaft 35, on the inner end of which is a lever 36, designed to be forced downward by the part carried by the locomotive, as described in connection 5 with the lever 28. It will be seen that the levers 28 and 36 are arranged at opposite sides of a track, so that it will be necessary for an operating device to be placed on one side only of a locomotive, and these levers, 10 it is to be understood, are to be placed a sufficient distance from the gate to operate the same before the locomotive reaches the gate.

From the inner end of the bar 22 a link 37 extends underneath a rail of the track and 15 is attached to the forward end of a longitudinally-curved resetting-lever 38, which is mounted to swing on a horizontal plane at the inner side of the track.

In operation, as a train approaches the gate, 20 the releasing-lever at the approaching side will be depressed, which will cause the locking-block 19 to be moved out of engagement with the sliding bar 22. The spring 11 is now free to draw upon the upper end of the lever 25 9, and consequently by drawing upward the rear portion of the gate-bar 4 will move the said gate down to its closing position, as indicated in dotted lines in Fig. 1. Of course during the sliding movement of the bar 22 to 30 release the tension of the spring 11 the resetting-lever 38 will be drawn toward the rail, so that when the locomotive reaches the crossing the flange of its forward wheel will engage against said resetting-lever, swinging it 35 inward or toward the center of the track, and consequently drawing the bar 22 to its locking position to be engaged by the block 19. This movement will again reset the spring 11 and the weight 5 will cause the gate to swing 40 to open position.

As indicated in Fig. 5, the gate, near its pivotal point, is provided with a double-hinge 39, which will permit the gate to be swung laterally in either direction. This will be found 45 of service should a person driving a team be caught between the gate and the track, or it may be swung inward from the opposite side to permit an attendant to pass through while the train is approaching.

50 While I have shown the gate as arranged at one side of the track, it is to be understood that a gate may be arranged at each side.

Having thus described my invention, I claim as new and desire to secure by Letters 55 Patent—

1. A crossing-gate comprising a frame, a gate-bar mounted to swing in said frame, a spring for moving said gate-bar to closing position, a sliding bar arranged at one side of the 60 track and operating to release the spring tension, a locking device for said bar, and devices actuated by a train for moving the locking device out of engagement with the sliding bar, substantially as specified.

65 2. A crossing-gate comprising a frame, a gate-bar mounted to swing in the frame, a

spring for moving said gate-bar to closing position, a sliding bar arranged at one side of the track and having connections for releasing the tension of the spring, a locking-block for the bar, means operated by a train for moving the locking-block out of engagement with the bar, and means operated by a train for resetting the sliding bar, substantially as 70 specified.

75 3. A crossing-gate comprising a frame, a gate-bar mounted to swing in the frame and weighted rearward of its pivot, a spring for moving the gate-bar to closing position, a frame arranged at one side of the track, a 80 sliding bar movable transversely through said frame and having connections for releasing the tension of the spring, a locking-block guided vertically in said frame, angle-levers mounted on opposite sides of the frame and 85 having pivotal connection with the block, rock-shafts arranged at opposite sides of the track and at opposite sides of the crossing, connections between said rock-shafts and the angle-levers, and levers mounted on said rock-shafts and adapted to be engaged by a part 90 carried by a train, substantially as specified.

4. A crossing-gate comprising a frame, a gate-bar mounted to swing in the frame, a spring for moving said gate to closing position, a frame arranged at one side of the track, a sliding bar movable transversely through said frame and operating to release the spring, releasing-levers arranged at opposite sides of the track and at opposite sides 95 of the crossing, connections between said levers and the sliding bar for releasing the same, a resetting-lever mounted to swing horizontally between the rails, and a connection between said resetting-lever and the sliding bar, 100 substantially as specified.

5. A crossing-gate comprising a frame having uprights and a cross-timber at the top, a gate-bar mounted to swing on one of the uprights, an angle-lever having connection with the gate-bar rearward of its pivotal point, a lever mounted on the cross-bar, a connection between the upper end of said lever and the upwardly-disposed member of the angle-lever, a fixed standard on the cross-bar, a spring 110 connection between said standard and the upper portion of the lever, an angle-lever at the opposite end of the cross-bar, a connection between the upwardly-disposed member of said angle-lever and the lower end of the 115 spring-holding lever, an angle-lever arranged at the base of the frame and having connection with a member of the last-named angle-lever, a frame arranged between the track and the angle-lever at the base of the frame, 120 a sliding bar movable transversely through said frame, a yielding connection between said lever and the sliding bar, a locking-block guided vertically in the frame, angle-levers mounted on the frame at opposite sides and 125 connecting with the block, rock-shafts arranged at opposite sides of the track and at 130

opposite sides of the crossing, connections between said rock-shafts and the angle-levers on the frame, levers on said rock-shafts, a horizontally-swinging curved lever between 5 the track-rails, and a connection between said horizontally-swinging lever and the sliding bar, substantially as specified.

In testimony whereof I have signed my name to this specification in the presence of two subscribing witnesses.

MACK C. BARRY.
